Patented June 20, 1916.

Inventor:
Walter E. Molins

By George Cushingier, Atty.

UNITED STATES PATENT OFFICE.

WALTER EVERETT MOLINS, OF LONDON, ENGLAND.

APPARATUS FOR PACKING CIGARETTES AND THE LIKE.

1,188,193.

Specification of Letters Patent. Patented June 20, 1916.

Application filed March 3, 1916. Serial No. 81,930.

To all whom it may concern:

Be it known that I, WALTER EVERETT MOLINS, a citizen of the United States of America, residing in London, England, have 5 invented certain new and useful Improvements in Apparatus for Packing Cigarettes and the like, of which the following is a specification.

The present invention relates to apparatus 10 for packing cigarettes and the like and a main object of the invention consists in forming the filling piece for directing the articles into the package in such a manner as to permit a free passage through it of 15 the carrier which feeds forward the articles to be packed. Owing to this free passage for the carrier, a continuous, uninterrupted feed of the articles to be packed is possible, such continuous feed being provided for by 20 the use of an endless band having carriers at fixed intervals as the feeding means.

The invention will be described with reference to the accompanying drawings, which show one form of the invention.

25 Figure 1 is a diagrammatic perspective view of the essential parts of the apparatus; Fig. 2 is a transverse section through the filling piece; and Fig. 3 is a similar view of a modified form of filling piece.
30 The slightly tapering filling piece 1 of known shape, which in the construction shown lies on the feed table 2, is provided with a slot 3, through which the shaft 4 of the carrier 6 fixed to the continuously moving 35 band 5 can project freely into the filling piece. The carriers are arranged at suitable intervals from each other on the endless band 5 and are adapted to push the cigarettes or other articles to be packed through 40 the filling piece into the package 7 destined to receive them, which is arranged directly behind the latter, or can be slipped over its smaller end, as shown. As the carriers continue to move forward, the cigarettes and 45 the package into which they have been fed are also carried forward and the package with its contents may then be removed from the carriers in any convenient or known manner.

50 Instead of the filling piece being provided simply with a slot for the free passage of the carrier, one of its sides may be omitted altogether, as shown, for example, in Fig. 3. In this case the table 2 may form the missing side of the filling piece.

Having thus described the said invention

and the best means I know of carrying the same into practical effect,

I claim:

1. In a cigarette packing machine, the 60 combination with a traveling band, of carriers on said band, and a filling piece so formed that the carriers may pass therethrough and deliver cigarettes to a box previously placed on the filling piece. 65

2. In a cigarette packing machine, the combination with a traveling band, of carriers on said band, and a box-holding filling-piece so formed that the carriers may pass therethrough and deliver cigarettes to a box 70 previously placed on the filling-piece and remove the filled box.

3. In a cigarette packing machine, the combination with a traveling band, of carriers on said band for conveying a desired 75 number of loose cigarettes through a channel formed by guides on each side of the carriers, and a filling-piece so formed that the moving carrier may pass therethrough at the same time filling and removing a box 80 previously placed on the filling-piece.

4. In a cigarette packing machine, the combination with a traveling band, of carriers on said band for conveying a desired 85 number of loose cigarettes through a channel formed by guides on each side of the carriers, and a tapered filling-piece so formed that the moving carrier may pass therethrough at the same time filling and removing a box previously placed on the 90 filling-piece.

5. In a cigarette packing machine, the combination with a traveling band, of carriers on said band for conveying a desired 95 number of loose cigarettes through a channel formed by guides on each side of the carriers, and a filling-piece formed with a slit in its side so that the moving carriers may pass therethrough at the same time filling and removing a box previously placed 100 on the filling-piece.

6. In a cigarette packing machine, the combination with a traveling band, of carriers on said band for conveying a desired number of loose cigarettes through a channel formed by guides on each side of the carriers, and a tapered filling-piece formed with a slit in its side so that the moving carrier may pass therethrough at the same time filling and removing a box previously placed 105 on the filling-piece.

7. In a cigarette packing machine, the

combination with a traveling band, of carriers on said band, and a box-holding filling-piece to which said carriers deliver, said filling-piece having a passage longitudinally thereof to permit the carriers to pass therethrough.

8. In a cigarette packing machine, the combination with a traveling band, of carriers on said band, and a box-holding filling-piece to which said carriers deliver, said filling-piece having a centrally disposed slot in the bottom thereof to permit the carriers to pass therethrough.

9. In a cigarette packing machine, the combination with a slotted table, a traveling band beneath said table, carriers on said band projecting upwardly through the table slot, and a box-holding filling-piece adjacent

said slotted table, so formed as to permit the passage of the carriers therethrough.

10. In a cigarette packing machine, the combination with a slotted table, a traveling band beneath said table, carriers on said band projecting upwardly through the table, and a box-holding filling-piece having a slot in its bottom coincident with the slot in the table to permit the passage of the carriers therethrough.

In testimony whereof I have signed my name to this specification in the presence of two subscribing witnesses.

WALTER EVERETT MOLINS.
